UNITED STATES PATENT OFFICE

2,439,459

SOUND PICKUP UNIT

William C. Eddy, Michigan City, Ind., assignor
to Television Associates, Inc., Chicago, Ill., a
corporation of Illinois

Application August 6, 1945, Serial No. 609,173

2 Claims. (Cl. 181—28)

1

This invention relates to sound pickup units and more particularly to such units for use as hearing aids.

Hearing aids, employing electrical amplification, have long been known, including both those types in which the amplified vibrations are air born and in which bone conduction is employed to transmit the amplified vibrations to the hearing system. The present invention relates particularly to units of the bone conduction type which are easy and convenient to use and are inconspicuous in use.

Another object is to provide a sound pickup unit in which the sound vibrations are transmitted to the hearing system through the teeth of the user. Preferably, such units may be in the external form of smoking implements, such as pipes and cigarette or cigar holders so that they are easy and convenient to handle and are relatively inconspicuous.

Still another object is to provide a sound pickup unit in which the efficiency of sound transmission can easily be adjusted to vary the effective volume of the unit. In one preferred construction, the unit is formed of two parts connected by an adjustable joint whose adjustment varies the efficiency of sound transmission between the parts.

The above and other objects and advantages of the invention will be apparent from the following description when read in connection with the accompanying drawings, in which—

Figure 1 is a sectional view with parts in elevation illustrating one form of unit embodying the invention;

Figure 2 is an enlarged section on the line 2—2 of Figure 1; and

Figure 3 is a view similar to Figure 1 of an alternative form.

The unit, as illustrated in Figure 1, is made in the form of a smoking pipe to simulate a conventional pipe in appearance. The unit includes a two-part body comprising a bit part 10 adapted to be gripped between the teeth of the user and a bowl part 11 connected to the part 10. The bowl part 11 carries a sound responsive device 12. This device may be similar to the usual sound transmitting device employed for bone conduction in which case it is connected to a microphone and amplifier unit 13. If preferred, the device 12 may itself be a microphone which picks up and transmits the sound vibrations to the body part 11. In either case, the sound vibrations which are to be received are transmitted through the device 12 to the body part 11.

The body parts 10 and 11 are connected by

2

an adjustable joint which is formed, as shown, by a cylindrical reduced extension 14 on the part 11. The part 10 is formed with a series of fingers 15 arranged annularly to fit around the extension 14 and to leave a space therebetween. A sleeve 16 of compressible material such as rubber, plastic compositions or the like fits between the extension 14 and the fingers 15 to form a part of the joint therebetween. It will be seen that the efficiency of sound transmission through the joint depends upon the degree of compression of the sleeve 16.

In order to vary the compression of the sleeve, the outer surfaces of the fingers 15 are conically tapered and are threaded to receive a tapered, threaded ring 17. As the ring is turned to move toward the larger ends of the fingers, it squeezes the fingers in upon the sleeve material 16 to compress it more tightly between the fingers and the extension 14. In this way, the efficiency of sound transmission through the joint can be adjusted to vary the effective volume of the sound received by the user of the device.

In use, when the user desires to pick up sounds, he has only to grip the mouth piece part 10 between his teeth and adjust the ring 17 to produce the desired effective volume. Sounds picked up by the device will be transmitted from the body part 11 through the joint and the mouth piece part 10 to the teeth of the user so that they will be audible to the user. By simply turning the ring 17 in one direction or the other to a relatively slight extent, the effective volume of the sounds can be adjusted to suit different conditions. Since the device simulates a conventional pipe, it is relatively inconspicuous in use while providing a highly effective sound pickup unit.

In the embodiment shown in Figure 3, the unit is made up in the form of a cigarette holder including a mouth piece part 21 and an outer socket part 22 which may hold a conventional cigarette or the like indicated at 23. Within the socket part 22 is sound responsive device 24 similar to the device 12 of Figure 1 which is supported to induce vibrations in the socket part in response to the sounds to be picked up.

The parts are connected by a joint construction including a tapered extension 25 on the socket part 24 covered by a sleeve 26 of compressible material. A series of fingers 27 on the mouth piece part fit around the sleeve 26 and are threaded and tapered on their outer surfaces to receive the adjusting ring 28. In this construction, due to the taper of the extension 25, adjustment of the joint may be determined partly by the extent to

which the extension 25 and the sleeve 26 thereon are forced into the space between the fingers and partly by adjustment of the threaded ring 27. Except for these specific differences and for the differences in external appearance, the unit of Figure 3 is substantially similar to that of Figure 1 and functions in the same manner.

While two embodiments of the invention have been shown and described in detail, it will be understood that these are illustrative only and are not to be taken as a definition of the scope of the invention, reference being had for this purpose to the appended claims.

What is claimed is:

1. A sound pickup unit comprising an elongated two part body whose parts are formed of hard vibration-transmitting material, a sound responsive device carried by one of the parts to set up vibrations therein in response to sounds which are picked up, the other part being relatively long and thin and terminating in a bit to be gripped between the teeth of a user, the parts being formed with interfitting joint portions, compressible material between the joint portions, and adjustable means to vary the compression of the material.

2. A sound pickup unit comprising an elongated two part body whose parts are formed of hard vibration-transmitting material, a sound respon-

15 sive device carried by one of the parts to set up vibrations therein in response to sounds which are picked up, the other part being relatively long and thin and terminating in a bit to be gripped between the teeth of a user, a reduced extension on one of the parts, a series of annularly arranged fingers on the other part fitting around the extension, compressible material between the fingers and the extension, and a nut threaded on the fingers variably to press them together so that they will variably compress the compressible material.
